BASAL METABOLISM DIAGNOSTIC
APPARATUSJohn L. Bloomheart, Toledo, Ohio, assignor to
Martha F. McKesson, Toledo, Ohio

Application February 27, 1940, Serial No. 321,080

5 Claims. (Cl. 128—2.08)

This invention relates to respiration equipment.

This invention has utility in gas administration, more particularly as to quantity, say of oxygen, consumed by a patient in a given time interval.

5 Referring to the drawings:

Fig. 1 is a side elevation, with parts broken away, of an embodiment of the invention as an apparatus of metabolism equipment eliminating water or liquid in the pneumatic trough type of 10 Patents No. 1,677,147, July 17, 1928, and No. 1,863,929, June 21, 1932;

Fig. 2 is a view from the right of Fig. 1, parts being broken away, showing the absorber to which 15 the respiration ducts are connected;

Fig. 3 is a section on the line III—III, Fig. 1, showing features of the ducts to the mask;

Fig. 4 is a section on the line IV—IV, Fig. 3, showing the perforate disk openable by cutting 20 out the duct connections;

Fig. 5 is an enlarged view partially on the line V—V of Fig. 2, showing the housing removed, the bellows in section, and the absorber cap likewise in section;

25 Fig. 6 is a bottom plan view of the cap on the line VI—VI, Fig. 5;

Fig. 7 is a section on the line VII—VII, Fig. 5, showing features of the drive for the chart in the record mechanism and some of the connections 30 for operating the record making device or pen;

Fig. 8 is a partial section on the line VIII—VIII, Fig. 1, showing the relation of the marking device or pen as to the chart-carrying feed roll and the mounting connections therefor;

35 Fig. 9 is a section on the line IX—IX, Fig. 2, of the inhalation connections from the absorber;

Fig. 10 is a section on the line X—X, Fig. 2, of the exhalation connections to the absorber;

Fig. 11 is a section on the line XI—XI, Fig. 9, 40 showing the passages in the absorber chamber and absorber cap;

Fig. 12 is a section on the line XII—XII, Fig. 11, showing the supporting screen in the absorber for holding the soda lime or other particles to remove carbon dioxide from the exhalation;

45 Fig. 13 is a detail view on an enlarged scale of the cord or cable length clamp or take-up in the transmission from the movable portion of the bellows; and

50 Fig. 14 is a medial longitudinal section through said connection or coupling.

Table legs 1 may carry table top 2 having seats 3 in which may be located cushioned feet 4 from a base having flange 5 resting on the table top 55 with deck 6 thereabove (Figs. 1, 5). This flange

5 has fitting 7 to which electric supply lines 8 extend, and therefrom by conduit 9 to synchronous motor housing 10.

Record mechanism

On this deck 6 is plate 11 (Figs. 5, 8) mounting switch 12 having indications 13 for "off" and "on" positions thereof. This switch 12 is thus effective to cut in synchronous motor 10 and thereby drive gear 14 (Figs. 5, 7) in mesh with gear 15 operating vertical barrel 16 (Figs. 1, 5, 8) having teeth 17 to engage in openings 18 of chart strip 19. This chart strip 19 may have coil supply 20 on vertical barrel 21 mounted on the plate 11 and be fed therefrom by bight 22 about guide 23 to this vertical barrel 16. From this guide 23 there are yieldable arms 24 about the barrel 16 to carry take-off channel or guide 25 anchored by screw 26 with the plate 11 to the deck 6.

20 Between the supply barrel 21 and this feed barrel 16 as drawing material from the supply barrel 21, there is located vertical stem 27 (Fig. 8) carrying bracket 28 mounting ink-carrying pen 29 as the marking device. This bracket 28, remote from its mounting the pen 29, has fork 30 to engage guide pin 31 and thereby locate the pen 29 in position toward the chart. This bracket 28 adjacent the fork 30 is provided with screw 32 mounting spring 33 adapted to clamp the flexible cord or cable in its connection to this bracket 28. This spring 33 may release the bracket 28 from the cord and thus permits ready shifting of the pen 29. As the operator may grasp knurled head 34 (Fig. 1) of the barrel 16 to feed the desired marked portion of the tape from the device 29, and as such is fed to clear tear-off bar 35, pull of this marked portion of the chart may be made to sever such from the reserve supply and a subsequent chart is thus in position for receiving attention.

Variable chamber or bellows

On the deck 6 is housing 36 (Fig. 5). Upon removal of such housing there is exposed bellows fixed section 37 having screws 38 which effect, through sealing means 39, connection of corrugated tube 40 as a bellows, say of yieldable or resilient material of gas-proof form, providing annular ribs 41 spaced by grooves 42. There is thus provided, from this fixed section 37 to relatively movable section 43, a variable capacity 45 chamber 44. This section 43 is connected by screws 38 and sealing packing 39 to complete the sealed assembly of this bellows section between 50 55

the heads 37, 43. This movable section 43 has tubular arms 45, with which may telescope threaded arm sections 46 having lock nut connections 47 therewith. This leaves arm sections 45, 46 in alignment from hub 48 as a rocking bearing on axle 49. This hub 48 has anti-friction bearing 50 in its cooperation with the axle 49 to minimize resistance to operation. This adjustment of the arm 45, 46, is effective in a nicety for determining the radial position of the bellows and accordingly the volume for the chamber 44 as to distention with the annular ribs 41 and the roots of the grooves 42 having rigidity against expansion radially. This means that the capacity is varied solely by the slant portions between these ribs and roots of the corrugations.

The housing 36 is provided with stop 51 which may at limit position of the movable section 43 abut stem 52 and thereby against the action of spring 53 unseat relief valve 54. This means that the bellows may normally be an element in a closed circuit against any escape, but should there be excess pressure beyond the limit for expansion or opening of the bellows, the bellows may not be ruptured but this position is effective for a pressure release. In this housing 36 and mounted on the deck 6 is bridge member 55 locating hook 56, from which extends tension spring 57 to minor arm 58 adjusted by set screw 59 in fixed position with the hub 48 for the arms 45, 46. This means there is short radius arm 58 effective through the spring 57 as a neutralizing factor against gravity disturbance in the matter of gas capacity in the chamber 44. There is thus provided in this bellows a chamber sensitive to gas volume therein and accordingly one which is effective against pressure disturbance.

Bellows evacuation

40 In practice hereunder, there may be a purpose to start from zero or empty bellows. To such end, handle 60 (Fig. 1) may be operated to throw arm 61 (Fig. 5) fixed with the handle 60. This arm 61 terminally carries roller 62 which, as the handle 60 is effective, may contact the movable section 43 and cause such to be thrown to the extent of collapsing the bellows toward the fixed section 37, thus causing any gas therein to pass therefrom by ventilation port 63.

Bellows position indicator

The housing 36 (Fig. 1) adjacent the handle 60 has fixture 64 locating window 65 in position to expose indicator arm 66. This arm 66 (Fig. 5) is mounted by clamp device 67 with an arm 46 and thus in the swinging of the movable section 43 discloses such position through the window 65.

Barometer

60 Inasmuch as the accuracy of diagnostic work is of importance, a disturbance of such by variation in barometric conditions it is well to take into account, and in removing the chart and making record from the machine herein it is of value to 65 endorse on the chart the barometric conditions prevailing. Accordingly, the housing 36 (Fig. 1, 5) has mounted therein barometer 68, the position of which may be disclosed through window 69, for taking readings thereof.

Bellows connection to the pen for the chart

The movable bellows section 43 at its arm 45 (Fig. 5) has connection 70 with flexible wire cord 71, having a tension spring section 72, passing about guide roller 73 to guide roller 74 (Figs. 5, 7,

8), thence about roller 75 to clutch 76 on the bracket 28, thence up to roller 77 and then through guide tube 78. This line 71 then extends about roller 79 to roller 80, and thence by roller 81 back to the connection 70 with the arm 45. There is thus provided a complete two direction control for the pen with spring section 72 maintaining such as automatically without slack or accurate functioning as the movable section 43 of the bellows may be shifted in the capacity variations.

The connection 70 is at the free end of flexible arm 70' anchored with sleeve adjustable by set screw 76" along the arm section 46. This is accordingly an adjustment to disclose a varying capacity in shift for the pointer or needle 29 as 15 the pen or marker.

The mask

From the deck 6 (Figs. 1, 3) at fitting 82 there is flexible arm 83 having clamping connection 84 mounting inhalation duct 85 and exhalation duct 86 in position adjacent Y-fitting 87 carrying mask 88. This fitting 87 has ports 89. Knurled head 90 may operate disk 91 to close off air flow by these ports 89 and thus allow respiration gas to pass by seat 92 through port 93 to and from the mask 88 in normal breathing operations. However, in the event the operator should desire the patient to become familiar with the mask before starting the diagnostic process, or otherwise wish to adjust the apparatus for functioning prior to test, the hand wheel 90 may be operated to unseat the valve 91 and cause valve disk 94 to seat at port 92, thus cutting off the ducts 85, 86, and placing the mask 88 in communication through the port 93 and the ports 89 with the atmosphere.

The absorber

Exhalation by the patient at the mask 88 is by way of the duct 86 to chamber 95 (Fig. 10) to unseat check valve 96 and thence by chambers 40 97, 98 (Fig. 11). This expiration check valve section comprises fitting 99 assembled by set screw 100 with cap 101 of the absorber. This cap 101 has concentric inner annular seat 102 and concentric outer annular seat 103. Soda lime chamber 45 having outer shell 104 may abut gasket in the seat 103. Inner tubular portion 105 of this soda lime device or absorber separates soda lime fragments 106 in this annular chamber from duct 107 providing passage from the chamber 98 50 to chamber 108 below screen or perforate bottom 109 supporting the soda lime 106.

Knurled head 110 on stem 111 has shoulder 112 (Fig. 2) to abut seat 113 on the cap 101. This stem 111 extends (Fig. 11) through this cap 101 and 55 through the chamber 107 to engage fitting 114 adjacent the chamber 108 as a base of the outer shell 104. This chamber 108 is in communication with the duct 107 by ports 115 through the fitting 114. Accordingly, upon unscrewing action at 60 the head 110, this stem 111 is freed from the fitting 114 in soda lime container which may be allowed to settle in freed position as to the cap 101. A drawing up of the stem 111 thus allows the chamber to be shifted clear of the deck 6 and 65 removed laterally for replacement with a substitute container for discharge and replacement as the soda lime may be spent or there be other occasion for recharging.

This exhalation gas, as reaching the chamber 70 108 and passing up through the perforate section 109 into and about the soda lime 106, therefrom may flow by chamber 116 (Figs. 11, 9) on the way to chamber 117. Between the chamber 116 and chamber 117 there may be located indicator or 75

glass cylinder spacer 118 having lower foraminous wall 119 and upper foraminous wall 120 therebetween to carry particles 121 of an indicator sensitive, say by color, to disclose presence of carbon dioxide as not removed by the soda lime. This indicator may be specially treated say to show a green or greenish color as the gas may be purified by the absorber. However, as the soda lime is depleted or exhausted and the carbon dioxide content builds up, this indicator 121 may depart from this green color, say to a brownish cast, thereby warning the operator that the charge in the absorber should be replenished or replaced.

Knurled head 122 on stem 123 mounts fitting 124 in assembling this chamber device 117 with the cap 131 and whether or not with this indicator therebetween. This gas as in the chamber 117 may be inhaled by lifting check valve 125 and thus, in chamber 126, pass to duct 85 en route to the mask. Window 127 may be positioned by fitting 128 in position to observe the functioning of this inhalation check valve 125. Window 129 (Fig. 10) may be positioned by fitting 130 to disclose position of exhalation check valve 96 as lifted for exhalation flow in the chamber 97.

This absorber in this circuit as described for inhalation and exhalation has its breathing balance for exhalation taken care of from the chamber 116 through connection 131 (Figs. 5, 9) to the port 63. Thus at exhalation the bellows is distended with gas which has had the carbon dioxide removed therefrom. At inhalation the bellows responds to return to the patient the gas from which the carbon dioxide has been removed.

35 Thermometer

As a further check beyond the barometer there is located adjacent the port 63 thermometer 132 having window portion 133 (Figs. 1, 2, 5). The operator may thus check on what may be the temperature of the gases after the purification. This is an additional factor which may be taken into account on the chart in disclosing the degrees of temperature of the gas which may be inhaled by the patient.

In the functioning hereunder, a supply cylinder 134 (Fig. 1) of oxygen may have reducing valve 135 with duct 136 therefrom to valve 137 (Fig. 2) from which extends opening 138 (Fig. 10) into the chamber 97. Thus into this closed circuit there may be introduced, independent of flow back through the check valve 96 to the patient, a supply of oxygen to distend the bellows to the desired amount as may be disclosed by the pointer 66. In this charging or replenishing operation for gas to operate under the diagnosis, the valve 94 (Fig. 3) may be seated at the seat 92 and thus insure against pressure operating to open the check valve 125 and therefrom avoid the supply of oxygen through the intake or inhalation duct 85 to the patient. In the base 6 clear of the switch 12 is pocket 139 (Fig. 5) in which may be located bottle 140 having stopper 141. This may provide a convenient source of ink or writing material for charging the pen 29.

It is desirable to have the chart position start at a vertical timed line of the chart as the motor has started. Accordingly, the knurled head 34 may bring such line into position at the pen 29. However, the pen need not necessarily mark the chart to this point, for pivotal mounting 142 (Fig. 8) permits this pen to be rocked back against stop 143 during this shifting and then brought into position against the chart with the spring 33 operated to release the clutch connection 78 with

the cable or cord 71 in positioning the point 29 at the desired height on the chart as to the cross lines. Release of the spring 33 then re-connects the pen to this transmission connection of the bellows. 5

In the operation hereunder, the mask 88 (Fig. 1) may be placed in position on the patient with the hand wheel 90 operated to have the valve disk 94 close off the inhalation and exhalation ducts 85, 86. The patient is thus given an opportunity 10 to become familiar with the position of the mask and normal breathing with the mask in position. The operator may through the handle 60 swing the bellows section 43 toward the section 37 to evacuate the bellows from any gases therein. 15 Then from the supply tank 134 of oxygen, there may be a supply delivered in the desired quantity through the valve 137 up to the expansion sought for the bellows, short of having the relief valve 54 open. The absorber is, of course, in position 20 as properly charged, and the indicator 121 is of the proper color disclosure. The oxygen supply may be cut off at valve 137, and the handle 90 operated to establish communication for the patient to effect breathing by way of the absorber 25 to the bellows for exhalation and inhalation from the bellows back to the mask by way of the indicator 121. In this swinging of the bellows to and fro, the indicator arm 66 discloses to the operator how the bellows is functioning in the matter of 30 the depth of breathing which the patient may have. The thermometer window 133 discloses the temperature for the breathing operation, and the barometer window 69 shows the atmospheric pressure. By throwing in the switch 12, the chart 35 feed is effective and the inked pen 29 may thus have its positions of shift duly recorded on the traveling chart in providing a graph of frequency of respirations and their range, incidental to which there is the depletion of oxygen disclosed 40 as such is removed by the absorber.

The cable or line 71, in a portion thereof which in normal functioning of the bellows would not require passing over a guide wheel, has an adjustable clutch connection for accuracy in length 45 variation. To this end, the cord 71 (Fig. 14) may pass into coupling section 144 to protrude through lateral opening in this cylindrical or cup-shaped end to have the cord terminate in knot 145. This section 144 having the cup-shaped end oppositely 50 therefrom carries externally threaded section 146 adapted to engage in companion section 147, which receives centrally therein the remote portion of the cord 71 to have such protrude from lateral opening 148 and be clamped in such position by the threaded portion 146 in cooperation with this section 147. It is thus possible to bring the tension of the spring 72 into a degree of uniformity in holding the indicator 66 with this spring 72 at all times serving to keep up the slack 55 at such maintained tension. 60

What is claimed and it is desired to secure by United States Letters Patent is:

1. Respiration apparatus embodying a closed circuit including a variable capacity chamber having a pair of sections, one of which is hinge mounted, an annularly corrugated tube connecting the sections and providing a bellows, and a neutralizing spring having connection to the movable section eccentric of the hinge and a fixed connection whereby stressing the spring away from mid-position of the movable section is effective for rendering the bellows approximately uniformly sensitive to gas volume in its range of capacity. 65

2. Respiration apparatus embodying a closed circuit including an annularly ribbed and grooved bellows section, a fixed and a movable section connected by the bellows section, a support for the sections, a stop for the movable section mounted on the support exterior of the sections and a relief valve for the bellows carried by the movable section and movable with the movable section away from the fixed section and toward the stop to be operated by the stop.
3. Respiration apparatus embodying a chamber for respiratory gas including movable means to disclose depletion of said gas volume therefrom, a housing enclosing the chamber, an absorber exterior of the housing having ventilation port connection with the chamber in assembly to provide a closed circuit, and a passage section in said circuit providing a chamber for a color responsive carbon dioxide indicator.
4. Respiration apparatus embodying a chamber for respiratory gas including movable means to disclose depletion of said gas volume therefrom, a

housing enclosing the chamber, a carbon dioxide absorber, a mask, ducts from the mask to the absorber and chamber in providing a closed circuit in one of which ducts the absorber is located, there being a passage section from the absorber providing a chamber, and indicator particles in the chamber adapted to respond through color change of the particles by presence of carbon dioxide in said circuit as flowing therewith.

5. Respiration apparatus embodying an absorber provided with a ported cap forming a support, an absorber chamber having an open top to abut the cap in providing a pair of endless sealed connections therewith, said chamber having independent passages from said connections in the cap forming from the cap a closed circuit, and a bolt through the cap adapted to engage the chamber to pull the chamber up to seating position, said bolt being operable to release the chamber for settling clear of the cap for lateral removal relatively to the cap.

JOHN L. BLOOMHEART.
